UNITED STATES PATENT OFFICE

HARRY F. SMITH, OF LEXINGTON, OHIO.

METHOD OF MAKING PRODUCER-GAS.

1,027,290.

Specification of Letters Patent.

Patented May 21, 1912.

Application filed December 9, 1909. Serial No. 532,273.

To all whom it may concern:

Be it known that I, HARRY F. SMITH, a citizen of the United States, residing at Lexington, in the county of Richland and

5 State of Ohio, have invented certain new and useful Improvements in Methods of Making Producer-Gas, of which the following is a specification.

My invention relates to an improvement 10 in the making of producer gas, and the object is to suspend the fine fuel in the combustion chamber and during combustion by means of an upwardly directed air current having varying velocities at different parts 15 of the producer, whereby the fuel particles will be separated, causing the large particles to be at the bottom and the lightest to be at the top of the producer, but the entire fuel bed supported upon the upwardly directed 20 air current.

Great difficulty has been experienced in 25 producing gas from fine fuel. In many types of producers the coal and air are fed into the producer together, the coal being reduced to a very fine powder, so as to be carried in suspension by the ingoing current of air. In producers of this character, where pulverized fuel is used, there must be a constant supply of fuel and air, as there 30 is no surplus fuel contained within the producer proper, and the slightest momentary interruption of the fuel supply causes an absolute stoppage of gas production until the fuel supply is reestablished. On account 35 of this difficulty for maintaining continuous conditions of supplying the fuel and air, it has been found advisable to supplement producers of this character with a zone of solid fuel, through which the highly heated products of combustion are passed, in order to establish a more stable gas quality, and at the same time to more perfectly reduce the products of combustion to combustible gases. When an attempt is made 40 to use finely divided fuels, that is to say, slack or culm, in producers of the ordinary type maintaining a solid fuel bed, great difficulty is experienced on account of the fact that it is difficult, if not impossible to main-

tain a sufficiently deep fuel bed to complete 50 the gas making reaction without at the same time creating difficulty from channeling and an uneven distribution of the blast.

In the accompanying drawings is disclosed 55 a vertical sectional view of an apparatus which may be used in carrying out my invention.

A represents the shell of the producer and B is the refractory lining. The internal contour of the producer is formed to produce 60 a uniform decrease in air velocity from the lowest to the highest position, which in this instance gives the interior of the producer a shape similar to that of an inverted cone. The bottom of the producer is provided 65 with a small or constricted opening forming a throat C through which the air is discharged into the producer. Below the producer is the ash pit or cinder box 1. Connected to the box is a pipe 2, which pipe 70 is connected to an air blower M; a line shaft L is adapted to receive power from any suitable source, and mounted upon the shaft is a pulley 3, from which an endless belt 4 passes. A pulley 5 on the air blower 75 M has the endless belt 4 passing therearound, and upon the rotation of the line shaft L, the belt 4 will cause the air blower to be operated for supplying the producer with a current of air, the supply of air being 80 governed by the speed of the shaft L.

A hopper E is mounted preferably at the top of the producer, through which the fine fuel is discharged into the producer. A feeder 6 is mounted in the hopper, causing 85 a discharge of fuel from the hopper into the producer, and connected to the feeder is a gear wheel 7. A variable speed shaft N is provided with a pinion 8 which is adapted to mesh with the gear wheel 7. A friction 90 wheel 9 is slidably mounted upon the shaft N and is adapted to engage the surface of the friction pulley 3; a lever 10 engages the friction disk 9 and is adapted to shift the friction pulley 3 for regulating the speed of the shaft N, and governs the supply of fuel 95 from the hopper to the producer. An out-

let D is formed in the wall of the producer through which the gas is discharged from the producer. A grate P is slidably mounted in the wall of the producer and is adapted to be received in the throat C for starting or kindling the fire. After the fire has been started the grate is withdrawn from the throat into the lining of the producer and the fire is suspended in the producer by 10 the air blast.

The fuel used in producing the gas is very fine, including practically no fuel that will not pass through a screen approximately one-quarter of an inch in mesh. Fuel 15 which is artificially pulverized could be used although I find that the screenings commercially known as "slack" and consisting of particles from the finest dust to the largest desirable size as specified, can 20 be very satisfactorily and economically used.

The apparatus is started by moving the grate into the throat C of the producer, whereupon the fire is kindled, and as soon as the fire begins to burn brightly, the shaft L 25 is caused to rotate, whereby motion is transmitted to the blower M, causing a supply of air to be discharged into the producer through the throat C which will support the fuel bed. Upon the rotation of the shaft L 30 and the operation of the air blower M, motion is also transmitted to the shaft N, causing the feeder 6 to be operated for discharging a supply of fuel to the producer. The coal or fuel is immediately ignited from the 35 fire below which is supported or suspended by the air blast, and combustion begins to take place in the regular way. As soon as the supply of fuel from the hopper E is well established and the combustion within 40 the producer regulated, the grate P is withdrawn, leaving the throat C unobstructed, upon which the apparatus can be brought up immediately to its full working capacity.

The supply of air which is discharged into 45 the producer will vary in velocity as it passes upwardly toward the top of the producer. The greater velocity will be at the bottom or throat of the producer, and the fuel, as it is discharged through the hopper, 50 will be separated as it comes into contact with the air blast, allowing the larger particles to pass down into the producer toward the throat C, where it will be supported by the air blast or current, and the different 55 sizes of fuel will be accordingly supported by the air blast, the finest of the fuel being supported at the top. For example, I have indicated in the drawings the large size fuel at K, the next at H, the next at G, and the 60 fine fuel at F. The velocity of the air above the point F being sufficiently low to prevent the fuel from being carried into the outlet D, and the velocity of the air at the throat C is sufficiently high to prevent the largest

pieces fired from passing through to the ash 65 pit. The throat C is made sufficiently small, so that for any normal operating condition of the producer the air velocity through the throat will be great enough to absolutely prevent any of the fuel from falling through 70 the throat, and the fuel is actually supported in its entirety on the ascending air current.

The separation of the fuel as above outlined, having the larger particles of the fuel at the throat of the producer and the finer 75 particles at the top, the larger particles will be first subjected to the action of the air blast, and are hence wholly consumed in the primary combustion. The hot products of combustion in passing upward into the producer, encounter successively increasing areas and surfaces of finely divided fuel offering a most favorable condition for the secondary or reduction of reaction required 80 for the formation of producer gas. Owing 85 to the fact that the particles of fuel are supported by the air current, there is no possibility of channeling as in the case of producers maintaining a solid fuel bed, but this arrangement enables definite zones of primary and secondary combustion to be maintained in the producer for the complete production of gas in a way that is not possible with other producers firing pulverized fuel. There is further an appreciable quantity of 90 fuel in the machine, and a momentary interruption will not result in an instantaneous interruption of gas making, since it would be necessary to consume entirely the mass of fuel suspended in the producer 95 before gas making would cease.

Of course, the supply of fuel and air pressure must be regulated so that there will not be a greater supply of air than coal, which would allow the air to pass on through 100 the gas outlet D without being consumed. On the other hand, if the fuel supply is greater than the air supply the fuel will continue to accumulate within the producer until the air current is no longer able to sustain it, when a part of the fuel will be carried out with the gas through the gas outlet D, and some of the fuel will pass through the throat C of the producer. The fuel, as it descends into the hopper will meet the 110 ascending stream of air having at different parts of the producer various velocities which will cause the fuel to separate under the influence of the air current, and each particular particle of fuel will remain in 115 that portion of the producer where the gas velocity is sufficiently great to support its weight.

The temperature within the producer is maintained sufficiently high to give either 125 partial or total fusion of the ashes. If the ashes are partially fused, small clinkers or cinders will be formed which will be car-

ried in suspension throughout the fuel bed on the supporting air current, but as they increase in size they will gradually descend and pass through the throat C to the ash pit, 5 due to the fact that they will become too heavy to be supported by the air current. If fusion of the ashes occurs, the fused slag will trickle down the lining of the producer and can be caught and tapped out into a 10 suitable slag twyer 12 located in the lining of the producer near the throat C.

In the operation of an apparatus in carrying out this invention, the diameter of the throat C was approximately six inches, while 15 the diameter of the producer chamber at a level with the outlet pipe D was approximately forty-two inches, while the vertical distance from the throat to the outlet was approximately one hundred inches. The gas produced did not differ materially in composition 20 from that of the ordinary producer gas from the same fuel. The gas burned freely and was of excellent quality, except for the admixture of considerable lamp-black. The 25 amount of lamp-black produced depended on the temperature at which the furnace was operated and did not offer any practical difficulty either in the operation of the plant or the use of the gas. The blast pressure 30 employed in this particular instance amounted to about twenty-four inches of water, or in other words, about one pound per square inch and the fuel was intermixed including from the finest dust to particles 35 which will pass through an approximately one-quarter inch mesh. The ash was found to fuse into a slag when the fusing point of the ash was sufficiently low, in which case it could be tapped out through the slag twyer, 40 as shown at 12. There was considerable tendency for slag to collect on the sides of the lining, from which it drained downward as it accumulated. When the normal fusibility of this ash was not great enough to permit 45 of its being handled in this manner, the semi-liquid slag was allowed to accumulate on the side of the lining until it began to obstruct the producer, when it was barred loose and discharged through the throat C 50 into the ash-pit. There was no tendency to complete oxidation, except where the fuel supply was very greatly reduced, when, of course, there was passage of unburned air through the fire, and a consequent heavy 55 production of carbonic acid and other non-combustible gases. No difficulty was encountered in maintaining partial combustion under a blast rate sufficient to support the fuel.

60 I do not wish to be limited to the means for feeding coal and supplying air to the producer, as any suitable means may be employed for supplying the air and fuel in practically continuous amounts.

I am aware that producers have been patented for the use of pulverized coal, but in this the fuel is not suspended in the air blast, but is simply carried into the producer along with the air and burned instantly, the air blast being generally directed in a horizontal, instead of a vertical, direction. In my invention I provide an upwardly directed air current having varying velocities at different parts of the producer, whereby the fuel particles are separated one from the other and the entire fuel bed is supported on the air current, the coarser particles being subjected to the most vigorous air blast and forming the basis for the primary combustion and the separated 75 particles, with very large surface in proportion to their mass, being made use of to secure the secondary or reduction reaction.

Having fully described my invention, what I desire to secure by Letters Patent 85 is:—

1. A method for producing producer gas, consisting in supplying fuel of varying sizes to the producer and supplying air to the producer for supporting the fuel. 90
2. A method for producing producer gas, consisting in supplying air to the producer, and supplying fuel of varying sizes to the producer in an opposite direction to the supply of air, and the fuel being suspended by 95 the air current.
3. A method for producing producer gas, consisting in continuously supplying air to the producer, and continuously delivering fuel of varying sizes to the producer which 100 fuel is suspended by the air current.
4. A method for producing producer gas, consisting in supplying air to the producer, having varying velocities at different parts of the producer, and supplying fine fuel of 105 varying sizes to the producer for separating the particles of fuel, and the fuel supported by the air current.
5. A method for producing producer gas, consisting in supplying an upwardly directed air current having varying velocities at different parts of the producer, and supplying fine fuel to the producer which is 110 separated and suspended by the air current, causing the larger particles to be at the bottom, and the smaller at the top. 115
6. A method for producing producer gas, consisting in supplying fuel to the producer, and supplying an air blast for supporting the fuel in suspension and separating the 120 fuel whereby the proper action may be obtained on the fine fuel.
7. A method for producing producer gas, consisting in supplying fuel to the producer, and supplying an upwardly directed air 125 blast for supporting the fuel in suspension and separating the fuel for obtaining the proper action on the fine fuel.

8. A method for producing producer gas, consisting in supplying fuel to the producer, and supplying air to the producer for suspending and causing the fuel to be in motion.

9. A method for producing producer gas, consisting in supplying fuel in particles of varying sizes to the producer and supplying air to the producer for suspending the

fuel and causing the fuel to be separated and 10 in motion.

In testimony whereof I affix my signature, in the presence of two witnesses.
